UNITED STATES PATENT OFFICE.

GEORGE S. MEYER, OF NEWBURGH, NEW YORK.

HORSESHOE.

1,187,361.

Specification of Letters Patent. Patented June 13, 1916.

Application filed March 1, 1916. Serial No. 81,380.

To all whom it may concern:

Be it known that I, GEORGE S. MEYER, a citizen of the United States, and a resident of Newburgh, in the county of Orange and

5 State of New York, have invented a new and Improved Horseshoe, of which the following is a full, clear, and exact description.

Among the principal objects which the present invention has in view are: to avoid 10 the loosening of anti-slipping devices when placed in service; to provide means for automatically increasing the grip of a shoe on said devices; and to simplify the means for accomplishing said result.

15 Drawings.—Figure 1 is a bottom view of a shoe and auxiliary calks therefor, said shoe being constructed and arranged in accordance with the present invention; Fig. 2 is a front edge view of a shoe constructed 20 and provided with calks of the character mentioned; Fig. 3 is a section showing a heel fragment of the shoe and an auxiliary calk attached in service relation thereto, the section being taken as on the line 3—3 in 25 Fig. 2; Fig. 4 is a horizontal section taken as on the line 4—4 in Fig. 3; Fig. 5 is a detail view showing the side of one of the auxiliary calks employed in the present invention.

30 Description.—As seen in the drawings, a shoe 10 having a toe clip 11, is provided with a series of turrets 12. The turrets 12 are provided to locally increase the thickness of the shoe structure for reinforcing 35 the same where sockets are bored to receive the tapered shanks 13 of the auxiliary calks 14.

As seen best in Fig. 3 of the drawings, the calks 14 have a cutting edge 15, a square 40 face 16, and a strengthening web 17. The shoe has a series of keys 18, each extending from the inner surface of one of the sockets formed in the turrets. The keys 18 are permanently and rigidly mounted in the 45 shoes and turrets to engage the top-opening tapered slot 19 cut in each of the shanks 13, as shown best in Fig. 5 of the drawings. The relation of the keys 18 and slots 19 is such as to require driving the calks to completely seat the shanks 13 in the sockets provided therefor. This operation results in 50 each of the keys 18 spreading the shanks 13 to more firmly grip the same in the sockets provided in the shoe and turrets 12 thereof. 55 Calks which are removably attached to

the shoe as at present constructed, are objectionable for the reason that it is found that the tapping thereof incident to the service loosens them sufficiently to permit them falling from the shoe.

60

It is obvious that when the calks are secured in the shoe by the use of the slotted shanks 13 and the keys 18 the above objection is avoided for the reason that the tapping which in the former construction tends 65 to loosen the calks, in the improved construction operates in just the reverse manner and tightens the hold of the shoe on the calks.

70

Claims:

1. The combination of a horseshoe having a series of open-ended sockets; a plurality of calks, each having a shank, said shanks being each provided with a top-opening slot formed in the side thereof; and 75 a plurality of wedge-shaped members rigidly mounted in said sockets for engagement by said slots.

2. The combination of a horseshoe having a plurality of tapered sockets; a plurality of removable calks, each having a tapered shank for fitting said sockets; and means for expanding said shanks as the same are driven into said sockets, said means embodying a key member permanently mounted 80 in and extending from the inner surface of each of said sockets, and a tapered slot formed in the side of each of said shanks.

3. The combination of a horseshoe having a series of open-ended upwardly-tapering 90 sockets, and a plurality of downwardly-tapering key members, each of said key members extending into one of said sockets from the side wall thereof; and a plurality of calks, each of said calks having a shank tapered in correspondence with said sockets, and each of said shanks having a slot formed therein, said slots tapering in conformity with said key members to be enlarged thereby when said calks are driven 95 into said sockets.

4. The combination of a horseshoe having a series of open-ended upwardly-tapering sockets, and a plurality of downwardly-tapering key members, each of said key members extending into one of said sockets from the side wall thereof; and a plurality of calks, each of said calks having a shank tapered in correspondence with said sockets, and each of said shanks having a slot 105 formed therein, said slots tapering in conformity with said key members to be enlarged thereby when said calks are driven 110 into said sockets.

larged thereby when said calks are driven into said sockets, said calks being further provided with squared faces, the edge of each of said faces adjacent said shoe when 5 in service, being removed therefrom to permit the insertion of a tool therebetween for prying said calks out of engagement with said sockets.

In testimony whereof I have signed my name to this specification in the presence of 10 two subscribing witnesses.

GEORGE S. MEYER.
